UNITED STATES PATENT OFFICE

HOWARD S. FRASER, OF NEW YORK, N. Y., ASSIGNOR TO THE SWARTWOUT COMPANY,
OF CLEVELAND, OHIO, A CORPORATION OF OHIO

FEED WATER REGULATOR

Application filed November 21, 1928. Serial No. 320,836.

This invention relates to feed water regulators and more particularly to a very sensitive control of the feed water valve for maintaining with great accuracy a constant level 5 of water in a boiler.

It is among the objects of my invention to provide a feed water regulator responsive to changes in boiler water level wherein great movements of the feed water valve are obtained in response to very small changes in the level of the water in the boiler drum. Another object is to create a force according to changes in the boiler water level and to integrate and multiply this force so that a 15 much greater force may be exerted on the feed water valve to control its opening. A further and more specific object is to position a fluid pressure generator in the plane of the water level of the boiler wherein pressure is generated as the water level falls and to use the pressure, so generated, to control an independent pressure in its effect upon a pressure actuated feed water valve. Another object is to arrange a connection between an 20 independent source of pressure which may be the boiler or feed water line and a pressure actuated feed water valve and to interpose in this connection a pair of valves simultaneously acting with opposite effects, one for establishing the connection and the other for 25 bleeding the connection to atmosphere.

Other objects will appear from the following description of a preferred form of my invention, reference being had to the accompanying drawing. The essential characteristics are summarized in the claims.

The drawing illustrates a layout of the parts comprising my invention.

Referring to the drawing, I have illustrated a boiler drum D wherein it is desired to maintain the water level along the line L and to which water is fed through a feed water pipe P. Connected in the feed water pipe is a feed water valve V. Disposed in the plane of the water level of the boiler is a fluid pressure generator F which for the sake of illustration may be of the type similar to that disclosed in the patent to Copley, No. 1,193,125 issued August 1st, 1916, or in the patent to Barrett, No. 1,650,108 issued No-

vember 22nd, 1927. The generator F is mounted on an inclined conduit 1 which communicates with the steam and water spaces of the boiler. Generally speaking, the generator comprises a closed chamber surrounding the conduit 1 which contains an expandible fluid, usually water, which is vaporized creating a pressure as the water level in the conduit 1 falls and permits the steam to move downwardly in the conduit. As illustrated in the patents mentioned above, it has been good practice to connect the generator directly to the pressure actuated feed water regulator valve so that the pressure created in the generator forced the valve open as the 60 water level in the boiler fell.

My invention constitutes an improvement over the substance of these prior patents in that the generator pressure is not exerted directly upon the feed water valve but in turn controls a greater pressure directing it to or away from the actuating parts of the feed water valve. In the prior patents the generators had imposed upon them heavy 70 duties and were of relatively large capacity. In my invention the generator is subjected to much lighter duty and may have a relatively small capacity which makes it more highly responsive to small changes in water level.

The feed water valve V may be of the diaphragm actuated type having a diaphragm chamber 10 wherein is disposed a diaphragm not shown, which acts on a valve stem 11 moving a valve closure member 12 onto its seat to close the valve. A spring 13 acting between the body of the valve and a nut 14 on the valve stem urges the valve open. The compression in the spring may be adjusted through the nut 14. A conduit 15 leading from the diaphragm chamber 10 conducts fluid to the chamber to establish pressures which tend to close the valve against action of the spring 13. Tapped into the feed water pipe, preferably between the valve V and the drum or leading from any source of pressure, preferably a constant one, is a conduit 16. In the conduit 16, I place a valve C which controls the flow through the conduit. Adjacent the valve C and joined thereto by conduit 17 is a valve G from which fluid may escape 80 85 90 95 100

to atmosphere or to a point of low pressure, as at 18. I have found it practical to use a pressure of about 125 pounds in the line 16 and in some instances where the boiler pressure exceeds this amount, a separate or reduced source of pressure may be preferred. As appears from the drawing, the conduit 15 joins the conduit 17. When the valve C is opened and when the valve G is closed, boiler pressure is established through the conduits 16, 17 and 15 in the diaphragm chamber 10 of the feed water valve which exerts a pressure tending to close the valve. The spring 13 of the valve V is adjusted so that such pressure will effectively close the valve and maintain it closed to prevent flooding of the boiler, at least when the boiler is banked.

When the valve C is closed and the valve G opened, communication is established through the valve G, the conduits 15 and 17 between the chamber 10 and atmosphere, so that the spring 13 may force the valve V wide open. It follows that intermediate relations between the valves C and G may be established which permit some flow through the pipe 16 and some discharge to atmosphere, so that various pressures are established in the chamber 10 to create various openings of the valve V according to the relative opening of the valves C and G. The valves C and G may be relatively small and highly sensitive as compared to the valve V.

As mentioned above instead of using the pressure from the generator F to actuate the valve V, I provide a conduit 20 leading from the generator and branching to pressure chambers 21 and 22 associated with the valves G and C respectively. The valves C and G may be similar in construction having closure members 23 and 24, movable through valve stems 25 and 26. Disposed between fixed parts of the valves and reacting upon the valve stems are springs 27 and 28, compression in which may be adjusted through nuts 29 and 30. As illustrated, pressure in the chambers 21 and 22 tend to move the valve stems downwardly and in the instance of the valve C downward motion of the valve stem moves the closure member 24 onto its seat to close the valve. In the instances of the valve G, the action is exactly opposite, that is downward motion of the valve stem moved the closure member 23 away from its seat to open the valve. Thus if the water level in the boiler falls slightly, the valve G is moved in a direction to open the passageway to atmosphere while the valve C is moved in the direction to close the passageway to the feed line. The correlation of movement between the valve or the lag or lead between them is established by adjusting the compression in the springs 27 and 28 by the nuts 29 and 30.

It has been mentioned above, that the valves are relatively small and highly sensitive so that a change in generator pressure

of only a few pounds is needed to move the closure members against the pressure in the line 16. A relatively small change in pressure created in the generator, which represents only a very small change in water level, is sufficient to move both of the valves through their entire range which changes the feed water valve actuating pressure from atmosphere to boiler pressure.

In operation, let us presume that the boiler is steaming and that for one of various reasons the water level tends to fall, then even with a very small fall in water level, the pressure in the generator F will be increased and the passage through the valve C will be restricted while the passage through the valve G will be enlarged. Thus the flow through the pipe 16 will be relatively smaller while the flow to atmosphere will be relatively larger thus relieving the pressure in the conduit 15 and the chamber 10 and permitting the spring 13 to open the valve V a greater amount to increase the feed and rehabilitate the water level. It is to be noted that the change in pressure in the generator F has a double effect in changing the pressure in the chamber 10 because it controls both the inflow and outflow of the conduit 17. It is also to be noted that during the normal operation of the boiler when the valve V is about half open that there will be a certain leakage through the conduit 16, valve C, conduit 17 and valve G. However, when the boiler is held under banked fires without load, the valve G is tight shut, thus preventing the escape of any fluid from the boiler.

From the foregoing it will appear that I have provided a very sensitive control, one wherein small changes in water level in the boiler are magnified in effect to get a very prompt and full reaction in the feed water valve and that the apparatus constituting my invention is simple in construction and adapted to expeditious installation. While I have described and illustrated a preferred form of my invention, I do not care to be limited specifically thereto or in any manner other than by the claims appended hereto.

I claim:—

1. A feed water regulator for a boiler including a pressure actuated feed water valve having a pressure chamber, a conduit leading to said pressure chamber from a source of fluid pressure, a pressure actuated valve in said conduit, a branch from said conduit leading to atmosphere, a pressure actuated valve in said branch, a pressure generator positioned in the plane of normal water level in the boiler connected to both of said last named valves, and means for separately controlling the response of said last named valves to the action of said generator.

2. A device according to claim 1 wherein said last named valves move in response to increases in generator pressures with oppo-

site effects, one to open and the other to close, to vary the pressure exerted in the pressure chamber of the feed water valve.

3. A device according to claim 1 wherein said last named valves move simultaneously in response to increases in generator pressure with opposite effects, one in a direction to open and the other in a direction to close, to vary the pressure exerted in the pressure chamber of the feed water valve.

4. A device according to claim 1 wherein increases in pressure developed in said pressure generator and exerted upon said last named valves increase the opening of the valve in the branch conduit and decrease the opening in the valve in the main conduit to relieve the pressure exerted in the pressure chamber of the feed water valve.

5. A device according to claim 1 wherein increases in pressure developed in said pressure generator and exerted upon said last named valves simultaneously increase the valve opening in the branch conduit and decrease the valve opening in the main conduit to relieve the pressure exerted upon the feed water valve causing an increase in the opening thereof.

6. In a boiler feed system, the combination of a pressure actuated feed water valve having a pressure chamber, a pair of independently acting valves each in communication with said chamber, one of said valves also communicating with a high source of pressure and the other valve communicating with a low source of pressure, means responsive to changes in boiler conditions for delivering a common operating force to both said last named valves, and independently adjustable spring means associated with each of said last named valves for synchronizing the response of said valves to said operating force.

7. In a boiler feed system, the combination of a pressure actuatable feed water valve, a control therefor comprising a pair of valves, a conduit joining said valves, a conduit leading from said conduit to said feed water valve, a connection from one of said valves to a source of fluid pressure, a connection from the other of said valves to atmosphere, one of said valves having a closure member moving downwardly onto its seat to closed position and the other of said valves having a closure member moving downwardly from its seat to open position, a valve stem in each of said valves connected to said closure members, pressure chambers in each of said valves, a diaphragm closing each of said chambers and associated with said valve stems, springs associated with each of said stems opposing the action of the diaphragms, means associated with each stem for adjusting the compression in said springs, a pressure generator associated with the boiler and having a conduit leading to both said dia-

phragm chambers for maintaining like pressures therein, whereby both valves are moved by a common actuating force one of said valves moving toward closed position while the other of said valves moves toward open position and whereby the lag or lead between said valves may be determined by a relative compression in said springs.

In testimony whereof, I hereunto affix my signature.
